(57) **CLAIM**

The ornamental design for a folding travel toothbrush handle, as shown and described.

DESCRIPTION

FIG. 1 is a front elevation view of a folding travel toothbrush handle of my new design, shown in a completely open configuration;

FIG. 2 is a left side elevation view thereof, the right side being a mirror image thereof;

FIG. 3 is a back elevation view thereof;

FIG. 4 is a top view thereof;

FIG. 5 is a bottom view thereof;

FIG. 6 is front, left side perspective view thereof, as seen from the bottom end thereof;

FIG. 7 is a back, right side perspective view thereof, as seen from the bottom end thereof;

FIG. 8 is a front elevation view of the travel toothbrush handle of my new design, shown in the configuration for brushing the teeth.

FIG. 9 is a left side elevation view thereof, the right side being a mirror image thereof;

FIG. 10 is a back elevation view thereof;

FIG. 11 is a top view thereof;

FIG. 12 is a bottom view thereof;

FIG. 13 is front, left side perspective view thereof, as seen from the bottom thereof.

FIG. 14 is back, right side perspective view thereof, as seen from the bottom thereof.

FIG. 15 is a front elevation view of the travel toothbrush handle of my new design, shown in the closed configuration used for traveling.

FIG. 16 is a left side elevation view thereof, the right side being a mirror image thereof;

FIG. 17 is a back elevation view thereof;

FIG. 18 is a top view thereof;

FIG. 19 is a bottom view thereof;

FIG. 20 is front, left side perspective view thereof, as seen from the bottom thereof; and,

FIG. 21 is back, right side perspective view thereof, as seen from the bottom thereof.

The broken lines shown near the proximal end of the grip portion in some of the views are for illustrative purposes only and form no part of the claimed design.
